CLOTH FORMING MECHANISM

Frederick N. Ross and Byron F. Everitt, Detroit,
Mich., assignors to Briggs Manufacturing
Company, Detroit, Mich., a corporation of
Michigan

Application February 1, 1932. Serial No. 590,276

8 Claims. (Cl. 45—138)

This invention relates to a forming mechanism adapted more particularly for use in connection with an upholstery forming or sewing machine.

One of the primary objects of this invention is to provide a mechanism which will be capable of engaging a continuously movable strip of cloth to form therein longitudinally extending seam ridges and to present these seam ridges to the sewing mechanism of the machine.

A further object of this invention is to provide a mechanism of the above mentioned character in which the several parts thereof will be adjustable to provide for variably spacing the seam ridges formed in the cloth.

Still further the invention contemplates the provision of a mechanism of the above mentioned character which will be relatively simple in construction and which may be conveniently associated with a sewing machine.

Numerous other objects and advantages of this invention will become more apparent as the following description proceeds, particularly when reference is had to the accompanying drawings, wherein:

Fig. 1 is a fragmentary side elevational view of a sewing machine showing a forming mechanism constructed in accordance with the teachings of this invention associated with the same;

Fig. 2 is a plan view of a portion of the structure shown in Fig. 1;

Fig. 3 is a sectional view taken substantially on the line 3—3 of Fig. 2;

Fig. 4 is a sectional view taken substantially on the line 4—4 of Fig. 3;

Fig. 5 is a sectional view taken substantially on the line 5—5 of Fig. 3;

Fig. 6 is a sectional view taken substantially on the line 6—6 of Fig. 3;

Fig. 7 is a sectional view taken substantially on the line 7—7 of Fig. 3;

Fig. 8 is a fragmentary sectional view taken substantially on the line 8—8 of Fig. 2;

Fig. 9 is a sectional view taken substantially on the line 9—9 of Fig. 2;

Fig. 10 is a fragmentary plan view with parts broken away of a portion of the structure shown in Fig. 3; and

Fig. 11 is a sectional view taken substantially on the line 11—11 of Fig. 10.

Referring then particularly to the drawings wherein like reference characters designate corresponding parts throughout all views, the reference character 15 designates generally a sewing or upholstery forming machine. The gen-

eral structure of this machine forms no part of this invention, the machine being fully described and parts thereof claimed in application Serial No. 490,034 filed by Frederick N. Ross and Horace L. Johnson on October 20, 1930, and entitled "Sewing looper mechanism". The machine is designed to unite by continuous lines of stitching, finish and lining fabrics, there being disposed between these fabrics suitable strips of cotton bat or the like.

The general form of the upholstery produced is illustrated in Figs. 6 and 7, and by reference to these figures it will be noted that the finish fabric F is formed with seam ridges S therein, while the lining fabric L is formed with portions N therein disposed adjacent the seam ridges S in a position to be stitched thereto. Disposed between the lining and finish fabrics are strips of cotton bat designated by the reference character B.

In general the sewing machine comprises a frame 16 upon which is mounted a source of power in the form of a motor 17. This motor drives a pulley 18 with which a belt 19 is engaged, this belt in turn engaging a pulley 20 mounted on a shaft 21. For coupling the pulley 20 to the shaft 21 there is provided a clutch designated generally by the reference character 22 and arranged to be actuated by a suitable hand lever or the like 23.

The shaft 21 extends into a casing 25 which contains reduction gearing, the take-off shaft of this reduction gearing being indicated by the reference character 26 and being provided with a sprocket 27 with which a chain 28 is engaged. This chain passes around suitable sprocket wheels for driving the several parts of the sewing machine such, for example, as the cloth and cotton bat feeding mechanisms.

The shaft 21 is also provided with a sprocket 29 with which a chain 30 is engaged, this chain driving the sprocket 31 which through suitable gearing drives a shaft 32 to operate the sewing needles of the machine.

The lining fabric L is fed from any suitable source to a point above the machine and is then fed downwardly to the sewing point in any desired manner. The thread T is also fed downwardly from above the machine to the sewing needles. The finish fabric F is fed to the machine from one side thereof, and the present invention is directed more particularly to the apparatus for feeding this finish fabric and for forming the seam ridges S in the same.

Supported by the frame 16 and projecting

laterally from one side thereof is an endless conveyor designated generally by the reference character 35. This conveyor is of the type disclosed in application Serial No. 462,620 filed by Frederick N. Ross on June 20, 1930, and entitled "Adjustable main conveyor". The conveyor is a latticed structure longitudinally but not transversely flexible. It comprises a plurality of transversely extending slats or bars 36 united into a belt-like structure by means of link chains 37. These chains are engaged by suitable sprockets 38 and 39 mounted on shafts 40 and 41, respectively, carried by the frame 16. The shaft 40 is preferably driven in any desired manner from the shaft 26, as for example by suitable sprockets on the shafts 26 and 40, these sprockets being engaged by a chain 42.

Each slat 36 is provided with a plurality of longitudinally spaced forming blocks 45. Each forming block is substantially U-shaped in cross sectional shape, being provided with a base 46 secured to its respective slat and being provided with the legs 47 which are spaced for a purpose which will hereinafter be more fully described.

Each slat has a corresponding number of similarly spaced forming blocks which in the upper flight of the belt form a plurality of substantially continuous longitudinal ribs which engage the finish fabric to preliminarily form in the same a corresponding number of longitudinal plates or ridges. These ridges are later formed into the seam ridges S in a manner which will hereinafter be more fully brought out.

Supported by the frame 16 above the conveyor 35 is a cross frame member 50. This frame member is provided with a longitudinally extending T-slot 51 for receiving the heads of clamping bolts 52, these bolts being adjustable longitudinally of the slot as will be readily apparent. Each clamping bolt supports a plate 53, and each plate has its lower edge disposed adjacent the top of the conveyor 35. The lower edge of each plate is provided with an inverted U-shaped recess 54, and the plates are so positioned transversely of the machine that each rib formed on the conveyor by the blocks 45 travels longitudinally of one of the recesses 54 during movement of the conveyor.

The plates 53 are of variable length, the longer plates being disposed centrally of the machine and thus centrally of the conveyor and the plates decreasing in length toward the sides of the machine. Each plate is provided at each end with a pair of sprocket wheels 55 disposed on opposite sides thereof, and engaging these sprocket wheels are suitable forming chains 56. These chains are driven by mounting the sprocket wheels 55 at the rear of the plate on a shaft 57, which shaft is provided with a gear 58 which is driven by a gear 59 on a shaft 60. This shaft is in turn provided with a sprocket wheel 61 which is driven by the chain 28.

The chains associated with each plate are of different length, the chain at the inner side of each plate being of greater length than the chain at the outer side thereof. Thus, as clearly illustrated in Fig. 2 of the drawings, the plates support long chains substantially centrally of the conveyor, and other chains decreasing in length toward both sides of the conveyor so that when the finish cloth is fed by the conveyor in the direction of the arrow in Fig. 2 of the drawing, the cloth will first be engaged adjacent its

center by the chains and then the chains on the opposite sides of the center will successively engage the cloth.

Carried by the frame 16 and disposed at the forward end of the conveyor is a transversely extending frame member 65 provided with a longitudinal slot 66. Suitably supported in this slot for adjustment longitudinally thereof as by the nuts 67 are supporting bolts 68, each of which supports one end of a T-bar 69. These T-bars are inclined downwardly to adjacent the forward ends of the plates 53 where the ends of these T-bars are supported by members 70 substantially U-shaped in cross section. The legs 71 of these supports may be disposed with their free edges in engagement with the top of the conveyor, as clearly shown in Fig. 9 of the drawings.

Mounted to one side of the frame 16 is a frame 72 which supports a roll 73 of the finish fabric. The fabric from this roll passes around suitable tension rolls 74 carried by the frame 72, around an idler roll 75 and then under a roll 76 which acts to spread or smooth the fabric. It will be noted that the fabric is wider than the conveyor 35 and that the members 69 are supported in converging relationship with respect to each other so that at their outer ends they are wider than the conveyor 35 or of substantially the width of the fabric and thus serve to support the fabric.

The fabric passes downwardly on the members 69 to the forward ends of the plates 53, the fabric strip being engaged first by the plates disposed centrally of the conveyor since these plates are the longest. As the fabric passes off the ends of the members 69, its under face is engaged by the blocks 45, while its upper face is engaged by the chains 56 on opposite sides of the blocks 45. This is illustrated in Fig. 4 of the drawings, and it will be understood by reference to this figure that ribs are formed in the cloth about the blocks 45 and within the U-shaped recesses 54 of the plates. It will be understood that because of the fact that the plates decrease in length toward the sides of the machine, the ribs will be formed in the cloth from the center outwardly so that the cloth will be gathered inwardly toward the center to form the ribs.

After passing under the plates 53, the seam ridges are maintained in the fabric by forming feet 80 and 81 which constitute furcations of members 82 adjustably mounted on a beam 83 which extends transversely of the machine and constitutes a rigid part of the frame thereof. It will be understood that, as illustrated in Figs. 5 and 6 of the drawings, the forming blocks 45 still engage the under face of the fabric F and hold the same upwardly between the forming feet 80 and 81.

Adjacent the inner end of the conveyor 35 and at the point where the forming blocks start moving downwardly out of the seam ridges, sewing plates 85 are mounted, one sewing plate being provided for each ridge S. These sewing plates are mounted for adjustment transversely of the machine as by the headed bolts 86 mounted in a T-slot 87 formed in a frame member 88, and each sewing plate is provided with a finger portion 89 arranged to extend into the seam ridges between the forming feet 80 and 81 and between the legs 47 of the forming blocks 45. Thus, as the forming blocks move downwardly, the seam ridges are stripped therefrom by the

sewing plates which hold the seam ridges in the position shown in Fig. 7 of the drawings.

Each sewing plate is provided with an open ended slot 90 through which the needle 91 of the sewing mechanism may reciprocate, it being understood that at this point the portion N of the lining fabric will be disposed adjacent the upper edge of the ridge seam S in a position to be stitched thereto. Each forming foot 31 is preferably provided with a looper housing 92 in which a looper mechanism operates in conjunction with the needle 91. The structure of the looper housing, the sewing plate, the forming feet and the structure and operation of the sewing mechanism all form no part of this invention, being described and claimed in the application first referred to herein.

From the above it is believed that the invention will be clearly apparent. The finish fabric 20 is fed toward the sewing mechanism by means of an endless conveyor, and this conveyor carries forming blocks which cooperate with each other to form substantially continuous ribs. These ribs engage the under face of the finish 25 fabric, while the upper face thereof is engaged on opposite sides of the ribs by former chains which, in cooperation with the forming blocks, form the seam ridges in the fabric. These 30 ridges are formed from the center of the cloth outwardly so that the cloth is gathered inwardly and so that further, any desired fullness may be produced in the cloth between the ridges to receive the strips of cotton bat B.

The several rib forming mechanisms may be 35 adjusted transversely of the machine to provide for adjustment of the spacing of the ribs transversely of the strip of fabric, and the forming feet and sewing plates may likewise be adjusted to correspond to the positioning of the forming mechanisms. The machine may be continuously operated, and the ridges will be continuously formed in the finish fabric as the latter is presented to the sewing mechanism.

While the invention has been described with 45 some detail, it is to be understood that the description is for the purposes of illustration only and is not definitive of the limits of the inventive idea. The right is reserved to make such 50 changes in the details of construction and arrangement of parts as will fall within the purview of the attached claims.

What we claim as our invention is:

1. In an upholstery forming machine, means 55 for advancing a strip of material, and a plurality of forming chains arranged in the path of travel of the strip of material and arranged to engage the upper face thereof, said forming chains being of variable length to provide for the successive engagement of said chains with said strip.

2. In an upholstery forming machine, means 65 for advancing a strip of material, and a plurality of forming chains arranged in the path of travel of the strip of material and arranged to engage the upper face thereof, said forming chains being of different lengths and the longer of said chains being disposed to engage the strip of material adjacent the center thereof, said forming chains being adapted to transversely ingather the strip 70 of material to form longitudinal ridges therein.

3. In an upholstery forming machine, an endless conveyor for advancing a strip of material, forming blocks on said conveyor arranged to form ribs longitudinally thereof engageable with the under face of the strip of material during travel thereof, plates supported above said conveyor and having recesses in their lower edges for receiving the ribs on the conveyor, and chains carried by said plates and engageable with the upper face of the strip of material and cooperating with the ribs on the conveyor to form ridges in the strip of material. 80

4. In an upholstery forming machine, means for advancing a strip of material, and means including a plurality of pairs of endless chains movable with said strip of material and engaging the upper face thereof to form ridges therein. 90

5. In an upholstery forming machine, an endless conveyor for advancing a strip of material, plates supported above said conveyor and arranged longitudinally thereof, said plates being of different lengths and being so arranged that their forward ends terminate at different distances from the forward end of said conveyor, and forming chains carried by said plates and arranged to engage the strip of material advanced by said conveyor under said plates. 100

6. In an upholstery forming machine, an endless conveyor for advancing a strip of material, means including endless chains supported above said conveyor and arranged to engage the strip of material advanced by said conveyor to form longitudinal ridges therein, and means for adjusting said chains transversely of said conveyor to vary the distance between the ridges formed by said chains. 105

7. In an upholstery forming machine, an endless conveyor for advancing a strip of material, forming means for engaging the strip of material advanced by said conveyor to transversely ingather the same to form longitudinal ribs thereon, and supporting beams associated with said conveyor for supporting the strip of material out of engagement with the conveyor prior to engagement of the strip of material with the said forming means. 115

8. In an upholstery forming machine, an endless conveyor for advancing a strip of material, plates supported above said conveyor and spaced transversely thereof, said plates being arranged longitudinally of said conveyor and the forward ends thereof terminating at different distances from the forward end of said conveyor, means including forming chains carried by said plates for engaging the strip of material to transversely ingather the same to form longitudinal ridges therein, and supporting beams disposed above said conveyor providing tracks for supporting the strip of material out of engagement with said conveyor prior to engagement of said forming chains with the strip of material, each supporting beam having its one end terminating adjacent the forward end of one of said plates and said supporting beams diverging outwardly from the forward ends of said plates to provide for the supporting of a strip of material wider than said conveyor. 120
